UNITED STATES PATENT OFFICE.

ERNEST P. A. WOLF, OF NEW YORK, N. Y.

LOOSE-LEAF BOOK.

1,078,116.

Specification of Letters Patent.

Patented Nov. 11, 1913.

Application filed September 9, 1912. Serial No. 719,270.

To all whom it may concern:

Be it known that I, ERNEST P. A. WOLF, a citizen of the United States, and resident of New York, in the county of New York 5 and State of New York, have invented certain new and useful Improvements in Loose-Leaf Books, of which the following is a specification.

This invention relates to loose leaf books 10 and has for its object means for assembling and holding between the side boards of the binding a greater or less number of leaves which can be quickly and readily added to or reduced, the leaves being substantially 15 bound under any circumstances, as will be more fully described in the following specification, set forth in the claims and illustrated in the drawings, wherein;

Figure 1 is a perspective view of a book 20 with its side thrown open to illustrate the invention; Fig. 2 is a perspective view of the binding thrown open; Fig. 3 is a view of the binding strips; Fig. 4 is a plan view of the rear edge of the leaves showing the locking means; Fig. 5 is a sectional view 25 through the rear edge of the book and binding strips; Fig. 6 is a similar view showing a reduced number of leaves in the binding; Fig. 7 is a similar view showing the 30 book opened; Fig. 8 illustrates the arrangement of the assembling rod. Fig. 9 is an enlarged view of a portion of the back plate and the tubular bearing.

This improved loose leaf book is provided 35 with resilient strips each secured to one side of the binder leaving the unsecured ends free, but coöperating to retain the leaves in the binder. Means are, however, provided to lock the two strips together, no matter how 40 many leaves may be in the binding, and these locks or latches also compress the leaves into suitable compass for ordinary use.

The book comprises loose leaves 10 having 45 at their rear edge rectangular slots 11 through which pass the spring strips 12 overlapping each other and secured to each inner side of the binding. There are several sets of these strips 12 employed, three sets 50 being preferable, and each strip is provided at one end with an eye 13 through which passes a rod 14 carried by tubes 15 attached to each side of the binding back plate 16. The eyes 13 occupy the intervals 55 between the tubes which are similarly placed on each side of the binding so that the strips

lie side by side in the slots of the book. The strips 12 each have a longitudinal row of perforations 17 which are adapted to register when the strips are placed side by 60 side in the slots.

On each side of the leaves is placed a thick sheet carrying on its inner edge a steel strip 18 perforated or slotted to conform with the leaves of the book, and to one or both 65 of these strips are pivoted the hooks or latches 19 to be swung into the perforations of the spring strips to retain the strip 18 at that point.

As will be seen in Fig. 6 the binder is 70 about half filled with leaves and the hook 19 is inserted in one of the perforations after the strip 18 has been forced down to its limit. The two binding strips are thus locked together and the book may be 75 opened and handled, the leaves being retained in a convenient position.

The position of the book in Fig. 7 shows how the springs occupy a reversed position from the normal, yet their relationship with 80 the leaves is not changed.

When the leaves are assembled, the spring strips on the lower board being permanent, they are passed through the slots of the leaves until the desired number 85 of the latter is assembled. The companion spring strips are then inserted in the slots beside the lower strips, and the two strips latched together by the hooks. The eyes of the upper strips are inserted in the intervals between the tubes 15 and the rod 14 inserted in the tubes and eyes. The rod 14 ordinarily has an upturned end 20 to insert and retract it, but when it is desired to render the binding more permanent and 90 prevent the removal of the rod, it is constructed as shown in Fig. 8, where it will be seen that the outer end is threaded and a tubular nut 21 is provided to be screwed on this end while in the tubes 15 so that the 100 rod may be removed only by those familiar with its construction.

This construction provides a simple and cheap means for binding books, pamphlets and periodicals temporarily or permanently, 105 and provides for the substantial binding of a limited number. It is obvious that more or less leaf slots may be used, and it will be seen in Fig. 4 that one of the hooks turns inward. This is to provide for the initial 110 operation in the binding, and when the sheets are assembled the middle strips are

first locked together. The outer strips are located and latched and the rod is then used to hold them to the back of the book. Other modifications may be resorted to without departing from the essential features above described.

The construction of the back plate and bearings is more clearly shown in the enlarged view Fig. 9, where it will be seen that after the tube 15 is formed, the end 22 of the sheet metal plate is formed into a clenching strip to engage and hold the edge of the cloth fly 23, which is pasted to the side board 24. The whole is then covered on the outside by a cloth or leather back strip 25, forming a solid and substantial binding and one in which loose leaves may be quickly placed and held.

What I claim as new and desire to secure by Letters Patent is:

1. In a loose leaf book, the combination with leaves having slots at one edge, of side boards and a back, tubular bearings on each side board, rods for the bearings, and flexible strips arranged in pairs in each slot and the strips of each pair being respectively attached to an opposite bearing rod.

2. In a loose leaf book, the combination with leaves having slots at their rear edges, of a back plate and side boards, resilient strips arranged in pairs adapted to enter the slots and each having an eye at opposite ends from each other, a rod connected with each side board and passing through the eyes of the strips on its side, and means, connected with the leaves, for locking same beneath a certain point on the resilient strips.

3. In a loose leaf book, the combination with leaves having slots at the edge, of a

back strip and side boards, tubular bearings in connection therewith, spring strips adapted to enter the leaf slots and having perforations and eyes, rods with threaded stems adapted to pass through the bearings and eyes, a nut for the stem of the rods to insert or remove them, and hooks on the outer fly leaf and adapted to enter the perforations.

4. In a loose leaf book, the combination with leaves having slots at the edge, of a back strip comprising a plate with tubular bearings, side boards, spring strips adapted to enter the leaf slots and having eyes and perforations, rods adapted to pass through the eyes and bearings, fly leaves with metal strips having slots to correspond with the slots of the leaves, and hooks pivoted on the metal strips on the outer fly leaf and adapted to engage the perforations of the spring strip.

5. In a loose leaf book, the combination with leaves having slots at the edge, of a back strip comprising a sheet metal plate with tubular bearings and clenching edges, back boards, flies carried by the clenching edges and adapted to be pasted to the back boards, perforated spring strips carried by the tubular bearings and adapted to enter the leaf slots, metal strips on the outer leaves, and hooks on one of the metal strips to pass into the perforations and retain the leaves.

Signed at New York in the county of New York and State of New York this 4th day of Sept. A. D. 1912.

ERNEST P. A. WOLF.
